HOLDER FOR A FOOD BOWL FOR PETS OR SIMILAR ARTICLE

Tony Robert, 5701 Southwest Freeway
Houston, Tex. 77027

Filed Mar. 8, 1971, Ser. No. 122,279

Term of patent 14 years

Int. Cl. D30—03

U.S. Cl. D30—13

Fig. 1

Fig. 3

FIG. 1 is a front, top and side perspective view of a holder for a food bowl for pets or similar article, showing my new design with the latch in closed position;

FIG. 2 is a front, top and right side perspective view with the latch in opened position; and

FIG. 3 is a rear, top and opposite side perspective view thereof, with the latch in opened position.

I claim:

The ornamental design for a holder for a food bowl for pets or similar article, as shown and described.
